UNITED STATES PATENT OFFICE.

HERBERT H. WATSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SLIDE CRADLE FOR WEFT-REPLENISHING LOOMS.

Application filed December 27, 1926. Serial No. 157,093.

This invention relates to improvements in bobbin releasing devices for weft replenishing looms and it is the general object of the invention to provide a construction wherein 5 the same releasing devices can be used for bobbins of different dimensions.

In co-pending application Serial No. 123,277 filed by Jennings et al., there is shown a multi-color weft replenishing 10 mechanism having so-called roll cradles which are proportioned to deliver bobbins of different lengths and diameters. The cradles shown in that application are given an angular movement about their axes first to receive a bobbin and then to expel the bobbin in order that it may move toward transfer position. The bobbin is shown therein of two forms, the long bobbins having a tip of 15 small diameter and the shorter bobbin having a tip of large diameter. It is an important object of my present invention to improve the general form of bobbin releasing cradles such as set forth in patent to Ryon No. 1,005,321 so they can function as do the 20 roll cradles of the aforesaid application.

With these and other objects which will appear as the description proceeds, my invention relates to the arrangements and combinations of parts hereinafter set forth, and 25 more particularly pointed out in the claims.

In the accompanying drawings, wherein a convenient embodiment of my invention is shown,

Fig. 1 is a vertical section through a multi-color magazine, having my invention applied thereto,

Fig. 2 is an enlarged horizontal section on line 2—2 of Fig. 1,

Fig. 3 is a view similar to Fig. 2 but showing the full length of one of the cradles,

Fig. 4 is an enlarged vertical section on line 4—4 of Fig. 3,

Fig. 5 is a view similar to Fig. 2 showing the long bobbin with small tip,

Fig. 6 is a view similar to Fig. 5 but showing the short bobbin with large tip,

Fig. 7 is an end elevation of that portion of one of the cradles which supports the tips of the bobbins, and

Fig. 8 is a partial view in elevation looking in the direction of arrow 8 in Fig. 3

showing the means for sliding the cradle members.

Referring to the drawings a magazine frame 10 is provided with a plurality of 55 bobbins slots 11 which guide the tips of the bobbins. Yielding supports 12 have downwardly and oppositely inclined surfaces 13 along which a bobbin may roll to a common transfer position from any one of the several 60 stacks. Each slot 11 is substantially the same in cross section as shown in Fig. 2. Each slot is of two widths, the wider portions being represented at 14 near the center of the magazine and the narrow portion being indicated at 15 and being deeper. The structure as set up in Fig. 2, so far as the slots 11 are concerned, may be the same as that shown in said copending application filed by Jennings et al. The bobbins are arranged in stacks, there being provision for 65 four stacks as shown in Fig. 1.

At the bottom of each stack is a bobbin releasing device or cradle and since these devices are substantially the same I will describe but one of them. Each cradle comprises an outer slide 20 having an upper lug 21 at one end thereof for the butt of the bobbin B. The other slide 22 is provided at the butt end of the bobbin with a lug 23 below the lug 21. A vertical bar indicated in cross section at 24 Fig. 3, carries a pin 25 which extends through slots 26 formed in the two slide members 20 and 22 in Fig. 8. The upper ends of the slots extend diagonally 80 relatively to the length of the cradles.

When weft exhaustion is indicated the vertical slide is raised so as to produce a relative sliding movement of said members, the lug 21 moving outwardly to release the 90 lowermost bobbin of the stack and the lower lug moving inwardly to form a rest on which the lowermost bobbin may fall. It is to be understood that the cradle or releasing device is normally empty and receive a bobbin at the time of indication of weft exhaustion and will hold the same until the indicating shuttle returns to the magazine side of the loom, at which time the slide 24 will move downwardly and the 95 slides will be restored to their normal position, slide 23 moving from under the butt 100

of the bobbin in the cradle to release the same so that the bobbin may fall down the guides and move toward transferring position. The matter thus far described is substantially the same as set forth in the aforesaid patent to Ryon and forms no part of my present invention. For the purpose of the present description it is assumed that the butts of the bobbin will be the same and for this reason those parts of the cradles and slides which cooperate with the bobbin butts, may be the same as those used heretofore.

In carrying my invention into effect I change the lugs on the tip end of the slides from the form shown in the Ryon patent to fit them for use on the bobbins having different characters of tips. Accordingly, I provide the upper part of inner member 20 with a pair of lugs the larger of which supports the longer bobbin tip T and is indicated at 30 and the smaller of which is shown at 31. Said lug 30 is provided with a narrow extension 32 which lies opposite a lug 31 and there is left between said lug 31 and extension a space slightly larger than the diameter of the smaller but longer tip T. In a similar manner member 20 is provided with a lower relatively large lug 33 and a shorter lug 34, the lug 33 having an extension 35 similar to extension 32 of the upper larger lug 30. The spacing between the lug 34 and the extension is the same as that between the lug 31 and the extension 32.

When a shorter bobbin of larger tip diameter is to be used it will occupy the position indicated in Fig. 6, the space through which the small tip passes being too small for the larger tip T' so that the latter will be supported by the lug 31 and extension 32 when above the cradle and by the lug 34 and extension 35 when in the cradle. In this way provision is made for the discharge of the two different kinds of bobbins as set forth in Figs. 5 and 6.

The tips of the longer bobbins T will lie closely adjacent the vertical inner wall of the frame 10 and will therefore be restrained against undue endwise motion but inasmuch as the butts of the bobbins must be in vertical alignment so that they may be properly transferred into the holding spring of the shuttle, the ends of the shorter bobbins will be spaced from the vertical walls. In order to provide means to prevent endwise motion of the shorter bobbins while in the cradle I incline the lugs 31 and 34 downwardly and also offset the extensions 32 and 35 downwardly so that the inner ends thereof are below the level of the corresponding larger lugs, as shown in Fig. 4. In this way the lower portions of the larger bobbins are below the upper surface of the large lugs 30 and 33 and are thus held against undue end-

wise movement. This is indicated in Fig. 4 where the full line circle shown in cross section represents the end of the small diameter bobbin and the dotted circle indicates the tip of the bobbin of larger diameter. The cradles are supported and guided in the frame of the magazine in the manner set forth in said figure and is more fully set forth in the aforesaid patent to Ryon.

From the foregoing it will be seen that I have provided bobbin releasing devices of the slide cradle type wherein a relatively long and small tipped bobbin and a shorter and larger tipped bobbin may be used in the same magazine, the cradles being equally effective to move a selected bobbin toward transfer position. It will further be seen that the slots 11 having two different lengths and widths are aligned vertically with the lugs on the ends of the slides adjacent the tips of the bobbins. It will also be seen that endwise movement of the shorter bobbins is limited so that the butts of all the bobbins may be in alignment to cooperate with the transfer mechanism. In using the cradles set forth herein it is possible to stack the magazine with two different kinds of bobbins, or if desirable, one stack can use bobbins of one length and another stack of another length.

Having thus described my invention it will be apparent that changes and modifications may be made therein by those skilled in the art without departing from the spirit and scope of the invention, and I do not wish to be limited to the details herein disclosed, but what I claim is:

1. In a weft replenishing mechanism having provision for guiding a stack of bobbins certain of which are relatively long with tips of small diameter and certain of which are relatively short with tips of large diameter, a pair of slidable members defining a bobbin releasing element at the bottom of the stack, each slide having a plurality of bobbin tip engaging portions certain of which hold one type and other portions to hold the other type of bobbins when the slidable members are in one relative position and said portions releasing both types of bobbins when the slidable members are in another relative position.

2. In a weft replenishing mechanism having provision for guiding a stack of bobbins certain of which are relatively long with tips of small diameter and certain of which are relatively short with tips of large diameter, a pair of slidable members defining a bobbin releasing device at the bottom of the stack, said members each having a plurality of bobbin tip engaging portions certain of which normally support one type of bobbin and other portions normally supporting the other type of bobbin, each member

normally effective to support either kind of bobbin, said portions effective to release either kind of bobbin when the members slide relatively to each other.

5. 3. In a weft replenishing mechanism having provision for guiding a stack of bobbins certain of which are relatively long with tips of small diameter and certain of which are relatively short with tips of large diameter, a pair of slidable members defining a bobbin releasing device at the bottom of the stack of bobbins, each member having bobbin tip engaging elements to support the shorter bobbins with large tips and having separate and other means to support the smaller tips of the longer bobbins, said elements being spaced apart a distance greater than the diameter of the tip of the longer bobbin, said members supporting either type of bobbin when in one relative position and effective to release either type of bobbin when moved relatively to each other.
4. In weft replenishing mechanism for a loom operating with two types of bobbins one of which is relatively long and of small diameter and the other of which is relatively short but of larger diameter, means to guide a stack of bobbins, and a device to support and control the discharging movements of said bobbins, said device including a pair of oppositely moving slide members having spaced bobbin tip engaging portions through which the longer bobbins of less diameter may pass when said members are in one position but which prevent passage of the short-

er bobbins of larger diameters when the members are in another position.

5. In weft replenishing mechanism for a loom operating with two types of bobbins one of which is relatively long and of small tip diameter and the other of which is relatively short but of larger tip diameter, a releasing device for the bobbins including a pair of members movable in opposite directions with respect to each other at the time the bobbin is to be controlled thereby, each member being provided with a plurality of bobbin tip supports for the bobbins, the support for the bobbin of larger tip being spaced apart sufficiently to permit the smaller tips of the other bobbins to pass therebetween.

6. In weft replenishing mechanism for a loom operating with two types of bobbins one of which is relatively long and of small tip diameter and the other of which is relatively short but of larger tip diameter, a pair of devices movable in opposite direction with respect to each other to control the movements of the bobbins, each member having a supporting lug for the longer bobbins and having also spaced supporting members for the shorter bobbins, the latter supports being depressed below the first named support so that a bobbin of larger diameter resting on the second named supports will be held against undue endwise movement by the first named support.

In testimony whereof I have hereunto affixed my signature.

HERBERT H. WATSON.
